(57) CLAIM

The ornamental design for a sectional sofa, as shown and described.

DESCRIPTION

FIG. 1 is a front, left and top perspective view of a sectional sofa, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings are included for the purpose of illustrating portions of the sectional sofa that form no part of the claimed design.
